US00D942646S

(12) **United States Design Patent** (10) Patent No.: **US D942,646 S**
(45) Date of Patent: **** Feb. 1, 2022**

(54) **ILLUMINATION AND IMAGING
INSTRUMENT**

(71) Applicant: **LIFE TECHNOLOGIES
CORPORATION**, Carlsbad, CA (US)

(72) Inventor: **Xin Mathers**, Poway, CA (US)

(73) Assignee: **Life Technologies Corporation**,
Carlsbad, CA (US)

(**) Term: **15 Years**

(21) Appl. No.: **29/737,991**

(22) Filed: **Jun. 12, 2020**

Related U.S. Application Data

(62) Division of application No. 29/669,949, filed on Nov. 13, 2018, now Pat. No. Des. 890,345, which is a division of application No. 29/581,075, filed on Oct. 14, 2016, now Pat. No. Des. 834,724.

(57) **CLAIM**

The ornamental design for an illumination and imaging instrument, as shown and described.

DESCRIPTION

The single view is a front perspective view of an illumination and imaging instrument showing my new design.

The broken lines illustrate portions of the illumination and imaging device that form no part of the claimed design.

1 Claim, 1 Drawing Sheet
